UNITED STATES PATENT OFFICE

150,063

DESIGN FOR A BOX

Marguerite Casseus D'Hennery, Paris, France

Application June 19, 1946, Serial No. 130,850

Term of patent 3½ years

(Cl. D58—12)

To all whom it may concern:

Be it known that I, Marguerite Casseus D'Hennery, a citizen of France, residing at 185 Boulevard Murat, Paris, France, have invented a new, original, and ornamental Design for a Box, of which the following is a specification, reference being had to the accompanying drawing, forming part thereof.

The figure is a perspective view of a box showing my new design.

The portion of the box not shown is the same as the portion illustrated in the drawing.

I claim:

The ornamental design for a box, substantially as shown and described.

M. CASSEUS D'HENNERY.
